UNITED STATES PATENT OFFICE.

EDGAR W. MERSEREAU, OF BROOKLYN, NEW YORK.

PUZZLE LOCK-BOX.

SPECIFICATION forming part of Letters Patent No. 269,306, dated December 19, 1882.
Application filed June 26, 1882. (No model.)

To all whom it may concern:

Be it known that I, EDGAR W. MERSEREAU, of the city of Brooklyn, in the county of Kings and State of New York, have invented a new and Improved Puzzle Lock-Box, of which the following is a specification.

My invention relates particularly to small boxes which are adapted to contain matches or other articles, and the covers of which are locked by devices hidden within the box, so that persons ignorant of their construction will find it very difficult to open them.

My invention consists essentially in the combination, in a box, of a cover and a body, which are pivoted together, and are adapted to be unlocked by a longitudinal movement of one part, so that the lid may be turned relatively to the body, one of said parts having a slot which receives the pivot and a recess or countersink in its outer side, and in the bottom of which the slot is formed, a cap on the pivot having in its inner side a corresponding recess or countersink, and a locking-disk adapted to fit wholly in either recess or countersink and bearing with its edge against the pivot. When the box is locked the disk rests in the recess or countersink in the part having the slot, and by bearing with its edge against the pivot and covering the slot prevents the part having the slot from being moved longitudinally relatively to the other part. When the box is to be unlocked, if the recess or countersink in the cap is not opposite the recess or countersink in the part having the slot, and wherein the disk rests, it is brought opposite the same by turning the cap, and the box is inverted, so as to allow the disk to fall into the recess or countersink in the cap, whereupon the part having the slot is moved longitudinally relatively to the other part to unlock the cover from the body, and the cover is swung on its pivot to uncover the box.

In the accompanying drawings, Figure 1 represents a plan of a box embodying my invention. Fig. 2 represents a longitudinal section of the box. Figs. 3 and 4 represent two end views of said box. Fig. 5 represents a longitudinal section with the box in an inverted position. Fig. 6 represents a plan of a box of slightly-modified form, also embodying my invention; and Fig. 7 represents a longitudinal section of the box shown in Fig. 6.

Similar letters of reference designate the same parts in all the figures.

Referring first to Figs. 1 to 5, inclusive, A designates the body of the box, which may be made of wood, and B designates the cover. At one end the two parts are connected by a pivot, C, and at the opposite end by a dovetailed tongue, a, on the body fitting in a groove, b, of corresponding form in the cover B. The body is intended to be uncovered by turning the cover on the pivot C, and in order to enable it to be turned the cover must first be moved or slid longitudinally to free the groove b from the tongue a. In order to provide for such longitudinal movement of the cover, I form in it a slot, c, which receives the pin or pivot C through it. In the top or outer side of the cover is formed a recess or depression, d, which receives a cap, D, adapted to turn upon the pin or pivot C, and in the inner side of the cap and the adjacent outer face of the cover are recesses or countersinks e, f, which are here represented as circular. The slot c is in the bottom of the recess or countersink f, as shown in dotted lines in Fig. 1.

E designates a disk of metal, corresponding in form to the two recesses or countersinks e, f, and adapted to fit loosely in either of them, so that when the two recesses or countersinks are coincident and the box is turned over the disk will drop freely from one into the other of said recesses or countersinks.

The outer side of the cap D may be divided into numbered spaces, like a dial, as shown in Figs. 1 and 3, and the recess or countersink e therein be so located that it will be opposite the recess or countersink f when the cap is turned or rotated to bring one particular figure to the line g—as, for instance, the figure 4. This is done to simulate a permutation-lock.

When the box is locked the disk E rests in the recess or countersink f and bears with its edge against the pin or pivot C, as shown in Figs. 1 and 2, so as to prevent the cover B from being moved or slid longitudinally to free the groove b from the tongue a.

To open the box the cap D must first be turned to bring the recess or countersink e opposite the recess or countersink f, and the box must then be inverted, as shown in Fig. 5, so that the disk E may drop from the recess or

countersink *f* into the recess or countersink *e* in the cap *D*. The cover *B* is then slid backward to free the groove *b* from the tongue *a*, and the box is turned right side up, whereupon 5 the cover may be swung sidewise on the pivot *C* to uncover the body *A*.

It will be seen that as soon as the cap *D* is turned slightly after receiving the disk *E*, or the cover is slid backward even slightly, the 10 recesses or countersinks are no longer in coincidence and there is danger of the said disk falling back into the recess or countersink *f* when the body is turned right side up. The disk being large enough to more than cover 15 the slot *c*, it can never fall into the slot and obstruct the manipulation of the cover.

Referring now to Figs. 6 and 7, *A* *B* designate respectively the body and cover of the box, and *C* the pin or pivot connecting them. 20 The body and cover are provided with the tongue *a* and groove *b*, and the cover *B* has the slot *c* and recess or countersink *f*, as before described. The cap *D'* is different in form from the cap *D*, before described, inasmuch as 25 it is of the same outline as the cover, except that it is shorter and forms a diagonal joint, *h*, with the cover *B*. The cap *D'* has the recess or countersink *e*, and when the cap is in the position shown in full lines in Figs. 6 and 30 7 this recess or countersink *e* is opposite the recess or countersink *f* in the cover. The box is then inverted and the disk *E* falls into the recess *e* in the cap, and by turning the cap into the position shown in dotted outline in Fig. 6 35 the disk is carried laterally away from the recess *f* in the cover. The box is then turned right side up, and the cover then slid back to

free the tongue *a* from the groove *b*, and the box opened by swinging the cover sidewise.

If desirable, the slot *c* might be formed in 40 the body instead of in the cover, and if so the recess *f* would be in the face of the body, which is now the bottom, and the cap *D* or *D'* would be applied to that side.

What I claim as my invention, and desire 45 to secure by Letters Patent, is—

1. The combination, in a box, of a body and cover pivoted together and adapted to be unlocked by a longitudinal movement of one part on the other, so that the cover may be 50 turned to open the box, one of said parts having a slot which receives the pivot, and having a recess in its outer side containing said slot, a cap on the pivot having in its inner face a corresponding recess, and a locking-disk 55 adapted to fit wholly in either recess and bear with its edge against said pivot, substantially as described.

2. The combination of the box *A*, the pivoted and sliding cover *B*, containing a recess, 60 *f*, the rotating dial-cap *D*, having a recess, *e*, and a locking-piece capable of entering either of said recesses, substantially as herein described.

3. The combination of the box body and cover 65 *A* *B*, provided with the tongue and groove *a* *b*, and the cover having the recess *f* and the slot *c* in said recess, the pivot *C*, the cap *D*, applied to the pivot, and having the recess *e*, and the locking-disk *E*, all substantially as described. 70
